UNITED STATES PATENT OFFICE

101,021

DESIGN FOR A DIAL OR SIMILAR ARTICLE

Joseph W. Astin, Atlanta, Ga.

Application May 22, 1936, Serial No. 62,772

Term of patent 3½ years

To all whom it may concern:

Be it known that I, Joseph W. Astin, a citizen of the United States, residing at 62 Georgia Avenue S. W., in Atlanta, in the county of Fulton and State of Georgia, have invented a new, original, and ornamental Design for a Dial or Similar Article, of which the following is a specification, reference being had to the accompanying drawing, forming a part thereof.

Fig. 1 is a front view of a dial showing my new design.

Fig. 2 is a sectional view taken along line 2—2 of Fig. 1.

I claim:

The ornamental design for a dial or similar article as shown.
